Albert Barnes
by H. G. Barnes
a. Attorney.

UNITED STATES PATENT OFFICE.

ALBERT BANDMAN, OF NEW YORK, N. Y.

SYRINGE.

1,293,667.

Specification of Letters Patent. Patented Feb. 11, 1919.

Application filed August 18, 1917. Serial No. 186,857.

To all whom it may concern:

Be it known that I, ALBERT BANDMAN, a citizen of the United States, residing at New York, in the county of New York and State of New York, have invented certain new and useful Improvements in Syringes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to syringes, particularly hypodermic syringes, and it has for its object to provide means for rendering practically fluid tight joints at the cap end and also at the needle end of the syringe. To that end the invention contemplates primarily a relatively soft or ductile metal washer possessing the characteristics of conforming closely to the face formation of the compression member acting thereon without spreading laterally to an extent to seriously impair the close contact union between the face of the compression member and face of the washer.

To the accomplishment of the foregoing and such other objects as may hereinafter appear the invention consists in the features hereinafter particularly described and then sought to be clearly defined by the claims, reference being had to the accompanying drawing forming a part hereof and in which—

Figure 1 is a vertical section through a syringe embodying the invention;

Fig. 2 is an end view of the compression ferrule.

In the drawing the numeral 1 designates the barrel of the syringe, 2 the plunger, 3 the end screw cap, 4 the needle point or cap, and 5 the finger rest, all of which may be of any suitable form or type of construction. Within the end cap 3 is a ferrule 6 through which the plunger rod passes. This ferrule may be made an integral part of the cap, or made separate and fitted therein and it serves as a compression member to make close contact between the packing washers when the cap is screwed tightly to place on the barrel. The face of the ferrule next to the washer with which it will contact is formed with an annular bead or ridge 6' which will indent or embed in the face of

the metallic washer against which it will bear so as to form a groove or depression corresponding in a general way to the shape of the bead. The metal washer is indicated 60 at 7, and is formed of a composition giving to the composition metal the characteristics of ductility without liability to spread unduly so that when compression is applied the compression member or a part thereof 65 will embed in the metallic washer and a fluid and air tight joint made between the compression member and washer. The composition for the purpose preferably consists of bismuth, pure tin, and lead, in suitable 70 proportions for the ends in view. Next to the barrel 1, and surrounding the plunger rod 2, is a metallic washer 8, similar to washer 7, and between the two washers is a washer 9 of leather or like material. The 75 end of the barrel next to the washer 8 is preferably formed with a bead or ridge 10 which will embed itself in the washer 9 when compression is applied to the several washers. This compression is applied 80 by screwing down the end cap 3 so as to press the ferrule against the washer 7 and the washer 9 against the end of the barrel, thereby forming indentations or depressions 85 in the two metallic washers corresponding to the beads or ridges on the ferrule and the end of the cap and also closely confining the leather washer between the two metallic washers. In the way mentioned a practically fluid and air tight joint is formed so 90 that there can not be leakage of either liquid or air at the end of the barrel.

At the needle end of the barrel a practically fluid tight joint is formed by providing a washer 11 of relatively soft or ductile 95 metal like the other washers mentioned which will surround the nipple 12 so that when the needle-point cap is screwed up on the nipple the edge of the cap, which will serve as a ferrule, will embed itself in the 100 metal washer which will be pressed tightly against the leather washer 13 which fits around the nipple and bears against the end of the barrel.

By providing the ductile metallic washers 105 at the needle end of the barrel and at the hand end of the barrel I am enabled to form a syringe, hypodermic or otherwise, which is practically fluid tight at both ends.

The invention can be embodied in syringes 110 of various types already on the market, and at a relatively small cost a most satisfactory

syringe can be provided which meets the conditions or requirements essential for the most efficient working of a syringe.

Having described my invention and set forth its merits, what I claim is:

- 5 1. In a syringe, the combination with the barrel and plunger-rod, of a ductile metallic washer and a non-metallic cushion ring both seated above the end of the barrel and encircling the plunger-rod, a compression member positioned above the ductile metallic washer and formed with an annular bead or ridge in contact with the metallic washer, and means for moving the compression member to embed its bead into the body of the metallic washer.
- 10 2. In a syringe, the combination with the barrel and plunger-rod, of a cap adjustably attached to one end of the barrel, a ductile metallic washer and a non-metallic cushion ring both encircling the plunger-rod and fitted within the cap to be seated above the end of the barrel, and a compression member within the cap and formed on its lower face
- 15 25 with an annular bead or ridge bearing against the metallic washer and adapted to be embedded in the body of the washer on adjustment of the cap.
- 20 3. In a syringe, the combination with the barrel and plunger-rod, of a cap adjustably

attached to one end of the barrel, the end of the barrel being formed with an annular upwardly extending bead or ridge, a compression member within the cap and formed with an annular downwardly extending bead or ridge, ductile metallic washers encircling the plunger-rod, one resting on said upwardly extending bead or ridge and the other bearing against said downwardly extending bead or ridge, and a non-metallic cushion ring encircling the plunger-rod, between said ductile metallic rings, said metallic rings adapted to have said beads embedded therein on adjustment of the cap.

4. In a syringe, the combination with the barrel and plunger-rod, of a ductile metallic washer and a non-metallic cushion ring both encircling an element of the syringe, the barrel being formed with a seat for the washer and ring, and a compression member formed with an annular bead or ridge bearing against the face of the metallic washer and adapted to be embedded in said washer on application of pressure.

In testimony whereof I affix my signature in presence of two witnesses.

ALBERT BANDMAN.
